UNITED STATES PATENT OFFICE

HARLEY H. MILLER, OF MIDDLETOWN, OHIO, ASSIGNOR TO THE MIAMI CABINET COMPANY, A CORPORATION OF OHIO

CABINET

Application filed October 15, 1928. Serial No. 312,418.

My invention relates to wall cabinets and is particularly addressed to providing a wall cabinet with means whereby articles such as razor blades and similar waste articles which cannot safely be left lying around may be easily disposed of.

In the drawings Fig. 1 is a front view of a cabinet showing door open. Fig. 2 is an enlarged cross section the central portion of which has been removed, and Fig. 3 is a similar view to Fig. 2 showing a modification.

In the drawings, A is the back of the cabinet, B is the door and C is the sides. As shown the cabinet is made of metal although any desired material could be used, but in making it of metal the outer edge of the sides and top and bottom C are bent in rectangular form so as to form the bead or edge D to which the door B is attached as shown in Fig. 1 by the hinges F. In placing these cabinets it is usual to place them so that they are attached to studding G with the beading D as the only portion that extends beyond the wall. In other words, the cabinets are usually embedded in the wall in this way. On the back wall of the cabinet over an opening I attach a plate H suitably held as shown by rivets II. This plate is stamped so that it has a portion J extending out from the back of the cabinet at an oblique angle to the back and a portion at right angle to the back as clearly shown in Fig. 2. In the portion J forming the right angle I provide an opening K extending across the stamped portion J. This opening is arranged in the back of the cabinet so that it comes between the studding to which the cabinet is attached and waste articles, such as razor blades, dropped through the opening K, pass between the walls of the building and are there deposited to remain until the building is destroyed or the walls removed.

This entirely disposes of such articles. In Fig. 3 I have shown a modification in which I provide, suitably arranged in the bottom of

the cabinet, a drawer L provided with a handle M adapted to slide back and forth. This drawer L has an upwardly extending portion N forming part of the back of the cabinet of about the width of the plate shown in Fig. 1. A plate similar to that shown in Fig. 1 having its upper portion free but adapted to rest against the back C of the cabinet is provided, the lower portion of the plate being bent so as to be parallel to the bottom of the drawer and is spot welded to the bottom of the drawer at O. As will be seen this plate has the portion J and the opening K through which the blades or other articles may be passed, and they drop into a compartment P from which they can be removed by taking out the drawer and slightly drawing the plate H away from the back end. The plate being a metal plate can be readily drawn back and will when released after all the articles have been dropped out of the compartment return to its normal position.

Claims:

1. In a cabinet, walls, one of said walls provided with a portion arranged obliquely to the wall proper and a connecting portion between such oblique portion and wall proper, such last mentioned portion being provided with an opening for the passage of articles into a space outside of the cabinet and back of a wall upon which it is mounted.

2. In a cabinet having back, top, bottom and side walls, one of said walls having an opening therein, a plate mounted upon said wall to cover said opening, said plate composed of a portion arranged parallel to the wall and fixedly secured thereto, a portion of said plate arranged at an oblique angle to said wall forming a guide into the opening through the wall to permit passage of articles into a space back of said wall.

3. In a cabinet having back, top, bottom and side walls, one of said walls having an opening therein, a plate mounted upon said wall to cover said opening, said plate com-

posed of a portion arranged parallel to the wall and fixedly secured thereto, a portion of said plate arranged at an oblique angle to said wall, a portion of said plate connecting said oblique portion and the wall, said last mentioned portion having an opening therein, said oblique portion forming a guide into said last mentioned opening.

5 In testimony whereof, I have signed my name to this specification.
